UNITED STATES PATENT OFFICE.

ZAIDA B. WEBB, OF NORWICH, CONNECTICUT.

GARDEN DOLL.

Application filed April 4, 1924. Serial No. 704,119.

My invention relates to improvements in dolls, and the object of my invention is to produce a doll which may if desired be made so as to be inexpensive, which is particularly attractive, and which may be made a means of instruction to a child. In consonance with this idea, I make the doll in general simulation of some natural horticultural or vegetable plant, for instance, the 10 face and head may represent a flower in bloom, the clothing can be made of flexible material such as cloth, paper, rubber, or other fabric which will simulate the leaves of the flower, and the feet and hands may be 15 buds or immature flowers. In carrying out the idea further, the body can be made in the form of, or to carry a retainer in which perfume may be carried, and exhaled, and the perfume can be as nearly as possible 20 that of the flower which the doll represents. The body can be stuffed or not as desired, and it can be conveniently formed on a wire which is flexible, but which will retain its 25 shape to the desired extent, so that the wire can be extended into the arms and legs, and when bent will stay in the position given. The doll is obviously exceedingly flexible, and means can be provided for hanging it up if desired.

Instead of a flower, the doll can be made in simulation of some garden vegetable, as for instance a beet, turnip, cabbage, or the like, in which case the root or head or bulbous part of the plant will represent the 30 head of the doll, and the body can be formed as already described, in simulation of the leaves of the plant, and the feet and hands can be smaller specimens of the root or bulbous part of the plant. If desired the 35 head of the doll can be stuffed with any suitable filler, or with an abrasive such as emery, so that it may be used as a needle cleaner. The doll can also be made with the head simulating some fruit or other natural 40 product, and the body clothed with leaves appropriate to the fruit represented.

Reference is to be had to the accompanying drawings forming a part of this specification, in which similar reference characters indicate corresponding parts in all the views.

Figure 1 is a front elevation of a doll showing my improvements.

Figure 2 is a broken side elevation thereof. 45 Figure 3 is a detail of the wire skeleton which can support the body, and

Figure 4 shows the doll in the form of a garden vegetable.

The drawings are by way of example, as it will be obvious that dolls embodying the 60 idea of the invention can be made in almost infinite variety. While the body can be made without any skeleton frame to support it, I prefer to use flexible wire 10, soft wire being better than steel, and this can be 65 twisted to form the part 11 of the torso, and single strands can be left to form the legs, which may have representations of buds 12 or small flowers or fruits or vegetables attached to form the feet. The hands can 70 likewise be formed by representations of buds 13, or other natural product of the plant, tree, or vegetable, and a wire 14 can form the arms, and this might, if desired, be the same wire that forms the rest of the 75 skeleton. I do not claim broadly the idea of the wire skeleton, as I know that it has been used.

The body of the doll can be stuffed as usual in such manufacture, or the leaves 80 15 which represent the clothing or drapery of the doll, can be attached directly to the skeleton frame. The important thing is to have the leaves 15 represent some natural leaf as nearly as possible, and in the illustration in Figures 1 and 2 I have shown the head and face made in simulation of a flower, the head portion 16 being stuffed, and having the petals 17 radiating therefrom. If desired the body can be stuffed 90 with sachet or other form of perfume, and it can have the container in any form, and the container can, for instance, be a portion of the body having an opening 18 at the top (see Figure 2) and closed by an ordinary 95 gathering string 19. This container may carry perfume appropriate to the flower, and will naturally exhale the perfume for a considerable period. It can be refilled when desired.

100 The doll being ornamental can be used either as a toy for children, or as a decoration, and to facilitate the latter use, it is preferably provided on the back with a hanger 20.

In Figure 4 I have shown the doll having a head 16^a in the form of a beet, or rather the root part of the beet, the body is clothed with representations of beet leaves, and the hands and feet are formed by representations of small beets 13^a and 12^a.

105 The foregoing description and the illus-

trations referred to will show clearly the characteristic features of the invention, and it will be understood that the doll can be made to represent flowers, fruit, vegetables, 5 or other natural products in great variety, without in the least affecting the invention, which as stated consists in having the face and head characteristic of the blossom, root, or other part of the plant, and the body 10 clothed with the leaves thereof, while the imitation can be carried further by providing the doll with some perfume, preferably characteristic of the plant or flower represented by the doll as a whole. It will also 15 be understood that any more conventional head and face can be adopted if desired.

The possibility of great variation in the structure while still being within my invention will be at once apparent. For instance, 20 the container carried by the doll, while primarily intended to carry a sachet or perfume, can be used as a container for many other things, which will make the structure more adaptable in some cases as a favor, and 25 the clothing while I preferably use flexible representations of natural leaves, can also be simply the stems and parts of the natural product, or the dress can be other things,

if the idea of having the hands and feet represent buds or immature specimens of the 30 product is preserved.

I claim:

1. A doll simulating a plant and comprising a head portion, petal simulating elements radiating from said head portion, a 35 body portion, leg portions and arm portions, leaf simulating elements secured to said body portion, leg portions and arm portions, and bud simulating elements secured to said arm and leg portions and defining hand and feet 40 portions respectively.

2. A doll simulating a plant, and comprising a head portion, petal simulating elements surrounding said head portion, a body portion having an opening therein adapted to 45 contain powder or the like, leaf simulating elements secured to said body portion, arm and leg portions, leaf simulating elements secured to said arm and leg portions, and bud simulating elements secured to said arm 50 and leg portions, and defining hand and feet portions respectively.

In testimony whereof, I have signed my name to this specification this 3d day of April, 1924.

ZAIDA B. WEBB.
